Application June 18, 1937, Serial No. 148,946
Renewed December 31, 1938

13 Claims. (Cl. 200—152)

This invention relates to mercury switches, and more particularly to such switches of the metallic envelope type as disclosed generally in our copending application, Serial No. 745,842, filed September 28, 1934. Briefly, the present invention is directed to switches using a metallic envelope as one electrode, with an open end in which is disposed a ceramic insert supporting a second electrode disc and forming therewith a mercury retaining recess, with suitable compression and sealing means in the end of the envelope.

Certain problems have arisen in connection with the commercial development and application of such switches to the solution of which the present invention is directed. One such problem has been the demand for quick acting small capacity switches used in sign flashers, and in controls for feed mechanisms where the switch is employed to make and break a circuit many times a minute.

In overcoming the problems arising in the use of such switches we have made certain advances in switch design and construction looking toward the dissipation of heat from the interior of the switch when in high speed operation, the control of the movable contactor to accommodate it to the required type of operation, and various modifications and refinements in the sealing of the open end of the envelope and improvements in the switch parts to provide an economical, simple and rugged switch of the metal envelope type.

We have found that the use of a compression disc of a moulded condensation product, such as "Bakelite" or the like, has several disadvantages when disposed in abutment against the resilient cushioning means which seals the electrode and the outer end of the ceramic insert and which is compressed axially into sealing position. The heat built up under repeated high speed operations causes the electrode to become heated, and this heat is transferred through the resilient sealing means to the laminated compression disc. This heat and pressure on the disc causes it to reform in a dished or frusto-conical form, opening up the seal and rendering the switch inoperative. This has been found to occur, even though the compression disc is supposedly not yieldable or reformable. Since we employ a partial liquid fill in such switches, the reforming of the disc allows the electrode stud to unseat, whereupon the liquid fill contacts the sealing means, which in some forms of the switch may be of rubber, and produces a sticky mass which causes the

switch to blow up. Another disadvantage in such switch structures resided in the fact that under heavy loads there was a tendency for a flash-over across the surface of the disc between the shell and the electrode stud. This produced a carbonized path along this surface which soon rendered the switch inoperative.

One object of the present invention is to provide a switch construction of this type employing as a compression disc a material that is not thermo-plastic, is a good heat conductor, and which will withstand high compressive stresses. Thus the disc will not yield or deform under heat and pressure, will dissipate heat from the electrode stud and from the resilient sealing means, and will be able to receive and transmit to the rubber the compressive stresses necessary to effect a proper seal. We have found that a ceramic material known commercially as "Isolantite" possesses all these characteristics and is of further advantage in that a flash-over across its surface will not deposit a carbonized path which tends to destroy the switch in a short time. The ceramic thus dissipates the heat from the resilient sealing means at a rate such that no deleterious action occurs in the seal, prolonging the effective life of the sealing means.

Another disadvantage in previous switches of this type has been the fragility of the ceramic insert forming the support for the internal electrode. Heretofore such inserts were formed with a long tapered raceway in order to provide a low operating angle for the switch. This produced a thin section which was easily broken or chipped. Also, the recess in the ceramic which forms, with the electrode, the mercury-retaining recess, had a relatively thin wall section, and under heavy loads tended to flash-over between the retained body of mercury and the shell or envelope. The annular cylindrical lip or shoulder also was disadvantageous, since the inserts are moulded, and the formation and drawing of such a shoulder was extremely difficult in the mold without chipping and cracking.

The present invention contemplates the provision of a ceramic of such design and thickness as to eliminate the possibility of flash-overs between the retained body and the surrounding shell, and provides a tapered shoulder which is much easier to form and which facilitates and increases the effectiveness of the sealing means. At the same time the long tapered raceway has been eliminated, reducing to a minimum any possibility of damage to the insert in its forming and assembly. We have found that the operating

angle can be controlled efficiently without such a raceway.

In this connection we have found that a ceramic commercially known as "Alundum" is especially adaptable for use in this connection. It is a relatively poor conductor of heat, but is highly refractory and is not affected or etched by an anhydrous alkaline liquid fill such as we employ and which is described in detail in our copending application, Serial No. 745,842, filed September 28, 1934. This ability to withstand etching under electric arcing and high temperatures when used in a switch of this type is of distinct advantage. Also, this material has materially less shrink than porcelain or other types of ceramic heretofore used, and hence can be formed within relatively close limits.

Another advantage obtained by the present invention resides in the use of a ceramic compression disc of the "Isolantite" type, which fits about the shank of the electrode and which has an inwardly directed tapered or wedge-like shoulder terminating against the face of the electrode. Since this material is a good conductor of heat, it transmits the heat from the metallic electrode directly, without passing this heat through the resilient sealing means. Also, since it is not reformable under heat and pressure it prevents the sealing means from getting around the edge of the electrode into contact with the liquid fill. The tapered shoulder produces a radial component of pressure on the seal and also insures giving a good seal at the outer face of the electrode about its periphery.

Another feature of the present invention resides in the manner in which the conductor leads are embedded in the end of the switch. We have used compounds or cements consisting of a cellulose acetate cement mixed with finely ground marble dust to embed the leads in the end of the switch, this material being applied in paste form and setting into a hard cement. However, this compound, commercially known as "green dip" has a relatively high shrinkage in setting, which cannot be entirely offset even with the granules of marble dust therein, and also is not temperature-resistant nor water resistant, being slowly combustible at kindling temperatures. Such a compound does keep the leads firmly embedded, however, and relieves the strain on the soldered or lug connections to the envelope and stud when tension is applied thereto. The compound is also advantageous in that it may be employed to cement the switch envelope to the interior of the moulded outer enclosing case, and to cement the moulded end cap to the case to enclose the switch, holding the parts firmly together to enclose the switch completely within a moulded insulating case.

In place of the cellulose acetate cement we may also use a compound known commercially as "Porcelute" which consists of a ceramic paste carried in a silicate binder. This material has great dielectric strength, is heat resistant and water resistant, and is also thermally conductive. When it has set it forms an even better embedding of the leads, and adheres firmly to other ceramics, and must be chipped away in small fragments in order to be removed. By using this material we find that no special lugs or terminal clips need be employed, and direct soldered connections to the shell and the stud may be made. However, the material does not adhere to "Bakelite" or similar moulded condensation products,

and hence cannot be used to cement the switch within an enclosing insulated shell. It is necessary, therefore, to employ the "green dip" for a final seal over the Porcelute in order to secure the case over the switch.

In experimenting with various end sealing cements for embedments of the leads, we have found that the product known commercially as "Sauereisen" has the advantages of Porcelute, is self-setting, and is an ideal insulating medium. This material is an electrical resistor even at high temperatures up to 2000° F. and has no water content, besides being insoluble in water after once setting. By using a ceramic compression disc having an end recess about the stud, the lead may be coiled about the stud within this recess and the entire end of the disc, stud and the adjacent portion of the lead may then be enclosed in this cement, forming an ideal end seal. The cap member may then be secured to the end of the enclosing case with the usual rubber cement, forming an effective water-proof seal about the leads and between the meeting edges of the end cap and enclosing shell. With rubber covered leads this forms an entirely waterproof switch closure.

Another feature of the present invention is the provision of a switch structure in which the resilient sealing means is maintained at a uniform temperature on both surfaces by employing heat conducting means in abutment therewith, whereby the heat transmitted to one side of the seal is transmitted therefrom at the same rate, maintaining the body of the sealing means at a uniform temperature. In one form of the invention this object is attained by employing ceramic heat conducting members on opposite sides of the resilient seal which act as uniform heat dissipators.

Still another object of the present invention is the provision, in a switch of this type employing "Alundum" as the ceramic electrode supporting insert, of a plurality of heat conducting paths for dissipating the heat rapidly away from the sharp cutting edge at which arcs may be generated. Since "Alundum" is in itself a poor conductor of heat, this prevents localized heating and insures a cool operating switch even under high speed operation.

In order to control, in switches of this type, the speed at which they can be operated, we preferably provide for varying the viscosity of the anhydrous alkaline liquid film which encloses the movable mercury contactor and the retained body of mercury. In a preferred form of the invention this film comprises triethanolamine. We have found that the viscosity of this material, which in itself is a tough, viscous film-forming substance, can be varied within a wide range by the addition of alcohol thereto, the viscosity varying almost directly in accordance with the amount of alcohol added to the fill. Thus for high speed operation, the fill is thinned out with alcohol to decrease its viscosity, allowing the mercury to move faster and thus reduce the time required between successive switch operations. The operating angle of the switch can also be controlled to some extent by controlling the viscosity of the liquid fill.

We may, if desired in order to obtain high speed switch operations, employ the inertia effect of the mercury for making and breaking contact, instead of tilting the switch. In other words, by moving the switch horizontally at high speed, the inclined raceway is driven like a wedge

under the body of mercury, which remains more or less stationary due to its inertia, thus raising this mercury into contact with the retained body. Similarly, by reversing the movement of the 5 switch body, the wedge is drawn out from under the main body of mercury, causing it to drop away from the retained body to break the circuit. Either mechanical, electrical or hydraulic means may be employed for imparting this high 10 speed oscillation to the switch envelope.

Under such conditions of high speed operation, the switch makes and breaks contact many times per minute, and consequently the thermal conduction attained as heretofore described is essential in order to maintain the switch operating 15 temperature within reasonable limits. This can be effected by using thermally conductive ceramics on opposite sides of the resilient sealing means, and by providing a plurality of heat dissipating paths from the point of heat generation 20 to the external portions of the switch.

In place of the conventional spring clips formerly used to mount mercury switches upon operating mechanisms such as heat, level or pressure 25 responsive devices, or on oscillating and reciprocating mechanisms, we have found that switches of the type provided by the present invention are peculiarly adapted for bracket mounting by means of brackets threaded or secured 30 to the protruding shank of the electrode, and a further object of our invention is to provide a switch structure having this type of bracket support.

Still another feature of our invention resides 35 in the provision of a structure whereby the switch leads may be brought out of the enclosing insulating case at any desired angle, either together or circumferentially spaced. This is attained by a novel type of enclosing shell having 40 an end cap cooperating with the end flange of the shell to secure this adjustability of lead position and which is adapted for completely enclosing the switch structure per se. This, in combination with the cementing of the 45 leads in embedded relation at the switch end, provides a switch which is waterproof and operable under water or oil, and which at the same time provides a decorative appearance highly desirable in installations where the switches are 50 visible.

Other objects and advantages of the present invention will be more apparent from the following detailed description which, taken in conjunction with the accompanying drawings, will 55 disclose to those skilled in the art the particular construction and operation of preferred forms of the present invention.

In the drawings:

Figure 1 is a vertical sectional view of a switch 60 of the present invention;

Figure 2 is an enlarged corresponding view of a switch of smaller capacity;

Figure 3 is a similarly enlarged view of a switch of intermediate capacity;

Figure 4 is a sectional view through a switch having a modified end seal construction;

Figure 5 is a similar view of a further modification of the end construction;

Figure 6 is an exploded perspective view of the enclosing shell and cap;

Figure 7 is a diagrammatic view illustrating the heat relationships of one form of the present type of switch;

Figure 8 is a sectional view of a mechanical

reciprocating mechanism for high speed operation;

Figure 9 is a view similar to Figure 8 showing another position in the operation of the mechanism;

Figure 10 is a somewhat diagrammatic view of an electrically controlled reciprocating mechanism; and

Figure 11 is a view, partly in section, of a mounting construction for switches of the present type.

Referring now in detail to the drawings, in Figure 1 we provide a switch comprising the metallic cup-shaped envelope 10 having the enlarged open end 12 joined to the main body portion of the envelope through a frusto-conical section 13. Within the open end of the envelope we provide the ceramic insert 14 which may be formed of any moulded refractory, although we preferably employ a ceramic commercially known as "Isolantite," or for certain installations we may employ a ceramic known commercially as "Alundum." The particular characteristics of these two types of ceramic will be described in detail hereinafter.

The ceramic 14 has a tapered frusto-conical surface fitting within the section 13 of the envelope, and is provided with the internal tapered throat or runway 15 leading to the radial shoulder 16, there being a sharp cutting edge defining the intersection between the runway and the shoulder.

The ceramic has a rearwardly extending cylindrical flange portion 17 of a slightly larger internal diameter than the diameter of the annular surface 18 which is adapted to receive the electrode disc 19 seating against the radial shoulder between the surface 18 and the internal annular surface of the flange 17. The face of the electrode 19 with the surfaces 16 and 18, is adapted to define a mercury retaining groove or recess of a dimension such as to maintain therein a stable body of mercury, indicated at 20. The particular dimensional relationships of the portions of the structure forming this recess are clearly set forth in the copending application, Serial No. 53,146, filed December 6, 1935 now Patent No. 2,132,921, issued October 11, 1938.

The body of mercury 20 is in continuous contact with the face of the electrode 19, and is adapted to be contacted for closing a circuit through the switch by the movable mercury contactor 22 carried within the envelope 10, and movable up the runway 15 upon tilting of the switch. We preferably provide a liquid fill of an anhydrous alkaline type, and preferably of the class of triethanolamine, which normally is a tough viscous liquid which forms a film over the mercury and prevents oxidation thereof, while at the same time increasing the normal meniscus height of the mercury as disclosed in detail in our copending application, first above-mentioned.

In order to effectively seal the interior of the envelope and the ceramic, we provide resilient sealing means such as indicated at 23 which may be formed of synthetic rubber or of any other suitable sealing material having a peripheral flange portion 24 which projects into the annular space between the flange 17 and the interior of the enlarged end 12 of the envelope. The radial portion 20 of the sealing means 23 seals the end surface of the flange 17 and the rear face of the electrode 18 about the electrode shank 25.

To compress the sealing means into sealing engagement with the respective surfaces, we pro-

vide in the present embodiment of the invention a ceramic compression disc 28 preferably of the "Isolantite" type which is engaged on its outer face by the terminal lug washer 27 and the annular compression ring 29. The disc is forced axially against the sealing means 28 by spinning over the outer end 29 of the envelope 18 to force the compression ring 28 and washer 27 against the outer radial face of the disc 28, moving this disc axially inwardly along the electrode shank 25 to produce axial compression of the sealing means 28. This, in turn, wedges the ceramic 14 firmly in position within the envelope and seals the interior of the envelope against escape of pressure therefrom, or admission of air or moisture thereto.

By employing a ceramic compression disc, we obviate the disadvantages formerly found in switches of this type in which "Bakelite" or a similar moulded condensation product was employed for the compression means. While "Bakelite" is not supposedly reformable under heat and pressure, we found that under the pressures obtained in a switch of this type, the "Bakelite" would reform into a concave shape allowing unseating of the electrode which, in turn, would allow the sealing means to come in contact with the liquid fill of the envelope, rendering the sealing means ineffective. Compression discs of the former type were also objectionable because of the fact that they did not act as good thermal conductors, and consequently prevented dissipation of heat from the sealing means 28 so that the heat transmitted thereto from the insert 14 and through the electrode 19 due to arcing within the switch remained in the sealing means, raising its temperature to a point such that it rapidly deteriorated and lost its sealing characteristics. Also, any flash-overs across the surface of the prior types of compression discs resulted in depositing a carbonized path over the surface which immediately reduced the dielectric capacity of the member, and in a short time resulted in failure of the switch under any appreciable loads. With the ceramic type of compression means, the heat dissipation from the sealing means is substantially equal to the transfer of heat thereto so that both sides of the sealing means remain at substantially uniform temperatures. Further, the ceramic being thermo-plastic, it will not be reformed under heat or pressure, and thus will retain its planar shape throughout the life of the switch. In addition, any flash-over across its surface will not produce a carbonized path so that the dielectric strength of the compression disc is maintained at all times.

Disposed outwardly of the compression disc 28 we provide a ceramic insulating spacer 38 about the electrode shank 25 which serves as an axial spacing member for the conductor leads 32 and 33 connected respectively to the terminal lug washer 27 and to the terminal lug 34 secured to the end of the electrode shank by the nut 35. We also may employ an insulating spacer disc 31 which may be formed of any suitable insulating material and which serves as a radial spacing means between the conductor leads. The switch envelope is preferably enclosed in an insulating case member 36 which receives the envelope and has the end portion 37 projecting axially therebeyond and adapted to receive the end cap member 38 having a peripheral flange 39 rabbeted into the flange 37 to provide an enclosed insulating case for the switch. The parts 36 and 38 are preferably formed of a moulded insulating ma-

terial such as "Bakelite." The details of construction of the insulating case will be described in detail in connection with Figure 6.

In order to seal the leads in position and to embed them so that any tension upon the leads will not result in disconnection of the leads from their terminal connectors, we preferably provide an end sealing compound or cement indicated generally at 40 in Figure 1. This compound may be of the type known commercially as "green dip" comprising a cellulose acetate base cement, into which is mixed fine finely ground marble dust for the purpose of reducing shrinkage upon drying and to prevent the formation of large voids or pockets in the cement. This material is slowly combustible, but has good insulating characteristics and serves as an embedding for the leads, taking the strain off of the soldered connections of the leads to the terminal lugs. This material is preferably applied to the space between the end 29 of the envelope and the insulating spacing disc 31 by means of a spatula, and it may also preferably be used in the space 42 between the end cap 38 and the insulating spacing disc 31. The material has the capacity to cement the end cap 38 to the member 36 to hold these members together in order to enclose the switch. The use of a cement of this type provides for embedding of the leads, and also serves to fill the space within the interior of the members 38 and 36.

However, we find that in order to secure better insulating qualities, it may be desirable to employ in the space 40 a material commercially known as "Porcelute," which is a cement consisting of kaolin mixed with a silicate binder, and which has relatively little shrinkage upon setting. This material is thermally conductive, but has high dielectric strength and is refractory in character. However, it will not serve as a cement for the parts 38 and 36, and if used in the space 40, the "green dip" must still be used to cement the end cap 38 to the case member 36. The manner in which we prefer to close the end of the switch will be described in detail in connection with Figure 5, although either of the methods thus far described may be employed if desired.

The use of the ceramic compression disc 28 and the ceramic spacer 38 is of distinct value insofar as dissipation of heat is concerned, and also in providing for high electrical insulation between the electrodes of the switch. Further, not being reformable under heat or pressure, these members maintain the electrodes in position, and also provide for retaining the desired compression upon the resilient sealing means.

Considering now the details of the switch construction shown in Figure 2 in which we provide a switch of a relatively small capacity such as of the order of one ampere, we provide an envelope 50 which may be formed of suitable stock having an axial bore 52 and an outer counterbored portion 53 forming therebetween a shoulder 54 against which a ceramic insert 55 is engaged. This ceramic insert is preferably of the type having high thermal conductivity while still being resistant to heating due to arcs within the switch. Within the interior of the envelope we provide a movable contactor 56 which is adapted to make and break contact with the projecting portion of an electrode 57 extending centrally through the insert 55 and held against inward movement by a shoulder portion 58 bearing against the outer face of the insert. Suitable resilient sealing means 59 is disposed against the rear face of the insert 55 and about the shoulder 58, and is com-

pressed into position by means of the ceramic compression member 60 which has a planar face portion engaging the rear face of the sealing means, and is also provided with a projecting portion 62 of reduced diameter forming an insulating radial spacer between the spun-over end 63 of the envelope 50 and the shank 64 of the electrode. A suitable metallic compression ring 55 is provided between the spun-over edge 63 and 10 the radial shoulder on the rear face of the compression member 60 to force the compression member axially inwardly along the counterbored portion 53 of the envelope, thereby compressing the sealing means 59 between the two radial 15 faces of the ceramic members 55 and 60. Suitable conductor leads 66 and 67 have their ends respectively soldered to the projecting end of the electrode shank 64 and to the edge 63 of the envelope 50. These leads are extending outwardly through openings 68 in the enclosing case member 69 which may be formed of wood or of a moulded insulating material. The envelope 50 may be press-fitted within the bore of the case member 69, and plastic cement of the type described in connection with the embodiment shown in Figure 1 may be introduced about the opposite ends of the switch as indicated at 70, although this may be omitted if desired.

This switch provides a mercury to metal contact, but since the loads carried thereby are relatively small, no disadvantage is occasioned by this type of contact. We may, if desired, introduce a liquid fill into the interior of this switch, although we find that it is not necessary, and for 35 high speed operation we preferably do not provide such a fill.

In this connection we may point out that the particular liquid fill which we employ is of a relatively viscous nature and has a tendency to slow down the movement of the mercury during tilting or reciprocation of the switch. For this reason we may desire to control the speed of movement of the mercury by varying the viscosity of the fill. For this purpose we find that suitable 45 control over the viscosity may be obtained by adding alcohol to the fill in the desired quantities to produce a proportionate reduction in the viscosity of the fill and thereby produce a corresponding increase in the speed or rate of movement of the mercury.

Considering now the switch structure shown in Figure 3 in which a relatively small switch of a capacity of five amperes or the like is disclosed, we provide a switch envelope 72 substantially of the type shown in Figure 1 but of smaller size, which is adapted to receive the ceramic insert 73 therein, this insert carrying the electrode 74 which projects into the interior of the envelope and is held against inward movement by a shoulder 75 formed thereon between the electrode head and the outwardly projecting shank portion 76. The rear face of the ceramic and the shoulder 75 of the electrode are engaged by resilient sealing means 77 having a peripheral flange portion 78 which engages about the annular shoulder formed on the insert, and provides both a radial and axial seal for the insert and electrode. The sealing means 77 is compressed into sealing engagement by means of the ceramic compression disc 79 of the type described in connection with Figure 2 having the projecting spacing portion 80 about the extending portion of the shank 76 for providing an insulating space between the shank and the spun-over end 82 of the envelope 72. In 75 connection with both Figures 2 and 3, it will be

noted that the sealing means is compressed between opposite faces of ceramic members and these ceramic members are preferably each of the type having relatively high thermal conductivity and high dielectric strength. Thus, the heat transmitted to the sealing means by the electrode carrying ceramics is dissipated therefrom at substantially the same rate by the compression ceramics, thus maintaining the sealing means at a substantially uniform temperature 10 on both faces thereof.

Within the envelope 72 we provide a movable mercury contactor 83 adapted to make and break circuit with the projecting portion of the electrode 74. It will be noted that the inner end 15 of the insert 73 is recessed, as shown at 84, to provide for increasing the contacting surface between the mercury and the electrode. However, the diameter of the electrode is such that the annular space between the electrode and the 20 wall of the envelope is less in cross-sectional dimension than the meniscus height of the mercury so that there will be no opportunity for the mercury to become locked in engagement with the electrode. The switch is preferably 25 enclosed by the case pieces 85 and 86 in a manner similar to that described in connection with Figure 1, suitable cementing composition 87 being applied over the portion 88 of the ceramic member 18 and within the end cap 86 to fill this 30 space and to embed the conductor leads 88 and 89 against displacement. These leads are led out through suitable notches formed in the interengaging edges of the case pieces 85 and 86 in a 35 manner which will be described in detail in connection with Figure 6.

Considering now the embodiment of the invention disclosed in Figure 4, the structure shown in this embodiment comprises an envelope 90 of the type corresponding to the envelope 10 of Figure 1, having the movable mercury contactor 92 therein preferably enclosed within a film of 40 the anhydrous alkaline liquid fill as indicated at 93. The envelope is adapted to receive the ceramic insert 94 which, in this embodiment of 45 the invention is preferably formed of "Alundum", which is a ceramic material having relatively poor thermal conductivity but being highly refractory in nature and not etched by an alkaline fill under electric arcing and high temperatures. This material has relatively little shrink 50 in moulding, and can be formed within relatively close limits. It is commercially sold as "Baker's alumina RA 518" and comprises aluminum oxide or a mixture of aluminum oxide 55 and silica dioxide. The particular insert 94 is provided with a relatively short internal raceway 95, and has a relatively thick section between the mercury retaining recess 96 and the adjacent wall of the envelope 90. This prevents 60 any possibility of a flash-over between the mercury 97 in the recess and the wall of the envelope through the insert which was a defect formerly found in inserts having a relatively long runway, and wherein the cross-sectional area 65 between the recess on the envelope was considerably less than that provided in the present insert. It was formerly thought that a long runway was essential for producing a low operating angle in such switches, but we have found that 70 this operating angle can be obtained without employing the relatively fragile type of insert heretofore thought necessary.

A suitable electrode disc 98 is supported within the shoulder portion of the rear of the ceramic 75

94 and is radially insulated from the envelope by the projecting shoulder 99 of the insert, which also serves to support the electrode in position. It will be noted that the shoulder 99 is provided 5 with a tapered annular surface 100 spaced radially inwardly of the inner defining surface of the enlarged end 102 of the envelope 98.

Resilient sealing means 103 is provided having the tapered peripheral flange portion 104 which 10 fits between the annular tapered surface 100 and the interior of the end 102 of the envelope, whereby axial compression of the sealing means produces a radial component of pressure due to this tapered surface, which increases the effectiveness of the seal. The sealing means is also provided with a tapered aperture 105 formed centrally thereof adapted to receive the forwardly extending tapered nose portion 106 of a ceramic compression member 107, preferably formed of 15 "Isolantite" having a high thermal conductivity.

The compression member 107 has the radial portion which is axially compressed against the rear face of the sealing means 103 to force the flange thereof into the annular gap about the 20 shoulder 99, and the tapered surface of the nose portion 106 also produces a radial component of pressure on the sealing means for increasing its effectiveness as a seal about the electrode face, and also against the inner periphery of the envelope. The ceramic 107 is provided also with a cylindrical reduced extension 108 which forms an annular insulating spacer about the shank 109 of the electrode to insulate the shank radially from the spun-over edge 110 of the envelope.

25 The compression member 107 is moved axially against the rear face of the electrode 98 and against the sealing means by the compression ring 112 which is disposed beneath the spun-over edge 110 of the envelope. The terminal lead 113 is connected to a terminal lug washer 114 disposed between the compression ring and the rear face of the disc portion of the member 107. The conductor lead 115 is connected directly to the shank 109 of the electrode by means of a soldered connection or the like. In order to 30 embed the leads to resist tension stresses tending to disconnect the ends from the washer 114 and the shank 109, we preferably apply a plastic cement 35 116 over the end of the compression member and about the end of the switch in a generally hemispherical form, this material preferably comprising "Forcelute", which adheres firmly to the compression member 107 and also to the metallic compression ring 112, and has keying engagement at the insulation of the leads 113 and 115 to firmly embed them therein. This material is quick drying, and is of the required dielectric strength to prevent any possibility of flash-over between the leads 113 and 115.

40 The switch envelope 98 is preferably enclosed within an insulating case member 117 conforming generally to the shape of the envelope and having the extending end 118 projecting outwardly beyond the spun-over edge of the envelope. An end cap insulating member 119 is provided having the peripheral axial flange 120 rabbed into the flange 118 and cemented thereto by means of a plastic cement such as "green dip," which fills the space between the cement 45 116 and the interior of the cap as indicated at 50 122.

55 Considering now Figure 6 in detail, it will be noted that the case member 117 has the enlarged end portion 123 which encloses the enlarged end 50 102 of the switch envelope. The edge 118 of the

portion 123 is provided with an axially extending notch portion 124 for the purpose of leading out a terminal conductor such as the conductor 113 of Figure 4. The member 117 is preferably formed of moulded "Bakelite" or the like, and 5 closely conforms to the external shape of the envelope 98. The end cap member 119 having the flange 120 is also provided with an axially directed notch 125 which is cut in beyond the rabbeted edge 126 which engages within the 10 10 annular edge 118 of the member 117. It will be noted that the lip or edge 126 is provided with a series of notched-out portions 127 spaced at various angles from the notch 125. The purpose of the notches 127 is to provide for selectively disposing the cap member 119 in any desired angular relation with respect to the case member 117, any one of the series of notches 127 being disposed in alignment with the lead notch 124 in order to prevent interference with the 20 conductor lead passing outwardly through the notch 124. Thus the cap member may be applied in any desired angular relation to the case member 117, and the leads may be brought out in any angular relation, depending upon the position of the notches 124 and 125. For example, as shown in Figure 4, the leads may be brought out on opposite sides of the case member when the notches 124 and 125 are so located or the leads may be brought out at the same point in the 30 periphery of the case, as indicated in Figure 3, in which the notches 124 and 125 would be disposed in alignment. This allows positioning of the leads in accordance with the desired installation of the switch, and to accommodate the 35 switch to various installations without requiring any modification of the component parts thereof.

Considering now in detail Figure 7, which is a somewhat diagrammatic view of a portion of the structure shown in Figures 4 and 5, it will be remembered that the insert 94 is of a material having poor heat conducting characteristics. However, the use of such a material is desired because of its high refractory nature and the 45 fact that it will not be etched or otherwise affected by the presence of the alkaline fill under high temperatures and electric arcs. This preserves the acute cutting edge between the mercury retaining recess and the runway 95, insuring 50 positive repeat performance of the switch, that is, the switch will open and close at the same angular positions during successive operations. We have found that other types of ceramics such as porcelain, "Isolantite" or "alsimag" 55 under high loads in the presence of the alkaline fill and electric arcs are subjected to an etching action which, in time, will reduce the sharp cutting edge desired and will erode or form a groove in the runway, destroying the 60 operation characteristics of the switch. It is necessary, however, when using an insert of the "Alundum" type to provide adequate means for dissipating the heat from the interior of the switch by employing a plurality of dissipating 65 paths other than through the insert. We indicate diagrammatically in Figure 7 the manner in which such heat dissipation can be effectively secured. Assuming that the point indicated at "X" is the point at which the heat is generated 70 by arcing between the mercury bodies 92 and 97 at the sharp cutting edge, the heat generated at this point will be transmitted through the body of mercury 92 to the shell or envelope 98, as indicated by the line 130. A portion of the heat 75

will also be dissipated by volatilization of the liquid fill, and the carrying away of the heat by the vapor to the surrounding walls of the envelope, as indicated by the arrows 132. Another portion of the heat will be transmitted through the body of mercury 87, and the metallic electrode 98 directly to the nose portion 106 of the ceramic compression member 107 which is formed of "Isolantite" or other ceramic of equal heat conductivity, and will pass through the ceramic 107 to the envelope as indicated by the line 133 or rearwardly out of the end of the switch along the shank 109 and through the member 107 as indicated by the line 134. This affords a sufficient plurality of heat dissipating paths so that no undesirable high temperatures are produced within the switch, and insures a cool operation switch under high loads which will maintain its operating characteristics for an indefinite period.

Considering now the embodiment of the invention shown in Figure 5, this switch is similar in construction to the switch shown in Figure 4, and corresponding reference numerals have been applied to those portions which are identical in nature to the corresponding portions of Figure 4. In the switch shown in Figure 4, however, the terminal washer 114 has been eliminated and the conductor lead 140 is soldered directly to the compression ring 112 and the spun-over edge 110 of the envelope. The compression member 107 has the reduced cylindrical portion 142 extending rearwardly along the electrode shank 109, and the shank end and the end of the portion 142 terminate in substantially the same plane. However, the portion 142 is provided with an axial recess 143 about the end of the shank 109 which recess is adapted to form an annular space about the end of the shank for receiving the bare end 144 of the terminal conductor 145. The end 144 is coiled within this recess about the shank, and is soldered thereto in any suitable or desired manner. Over the end of this recess and the end faces of the shank end portion 142 of the member 107 we preferably apply a plastic self-setting cement of the type commercially known as "saureisen" as indicated at 146. This cement is an electrical resistor at extremely high temperatures, running up to 2000° F., and upon setting has no water content whatsoever. Further, it is not resoluble in water and consequently provides a waterproof enclosure for the end of the switch. It is capable of adhering firmly to ceramics or refractories, and forms a good embedment for the leads to relieve tension strains upon the connections of these leads to the electrodes. If desired, the material shown at 146 may be applied over the entire end of the switch, taking the place of the material or cement indicated at 116 in Figure 4. However, we find that the case parts 117 and 118 can be very effectively cemented together by using ordinary rubber cement, as indicated at 147, and by using such cement, we may also positively seal the notches 124 and 125 about the conductor leads in such manner that the interior of the case members 117 and 118 are completely sealed against the entrance of moisture or the like, besides forming a positive bond between the case members preventing their separation. As a result, the interior of the cap member 118 and the end of the switch may be left open as indicated at 148, and the switch is capable of being operated when immersed in water or oil, or any simi-

lar fluid, this operation being enhanced by providing rubber coated leads to the electrodes.

It is to be understood that the cement as described in connection with Figure 5 may also be employed as an end sealing plastic for any of the embodiments of the invention shown in the present application, and may supplant the use of either "Porcelute" or "green dip" where conditions require a high dielectric strength with equally high thermal resistance, and also require that the cement be waterproof.

It will be noted that by employing the tapered surface 100 on the ceramic insert 94, the insert may be easily withdrawn from the mould due to the draft on this surface, and consequently the danger of cracking or chipping this flange is materially reduced. It is therefore to be understood in connection with the embodiment of the invention shown in Figure 1 that the ceramic shown therein may be of the form shown in Figures 4 and 5 with the flange 11 being formed with a tapered external annular surface. This may also be provided for the ceramic 13 of the embodiment shown in Figure 3. Also, the insulating spacing disc 31 of Figure 1 may be omitted, and the spacing member 38 may be extended outwardly to the end of the shank substantially in the manner shown in Figures 4 and 5, if so desired. This extending portion of the compression member may be either formed separately or as an integral part of the compression disc, as clearly shown by an inspection of Figures 1 and 2.

While ordinarily the switches thus far described are adapted to be operated by tilting the same from a horizontal position in order to provide for movement of the mercury contactor toward and away from the electrode or the retained body of mercury for high speed operation, it may be desirable to produce operation of the switch without tilting action. In the switches shown in Figures 2 and 3, this may be readily accomplished by reciprocatory movement of the switch since inertia of the mercury will be sufficient to hold it substantially stationary, and the switch body can be reciprocated to move the electrode into and out of contact with the mercury. However, the other forms of switches having the spun-over end and wedge shape type of internal runway may also be operated by reciprocatory longitudinal movement of the switch body, and reference is now made to Figures 8 and 9 disclosing one form of operation mechanism for accomplishing high speed operations of such switches.

Considering these figures in detail, we provide a supporting base member 150 having suitable supporting means 152 adapted to provide a journal for a rotatable shaft 153 extending transversely of the base member 150, and carrying a cam 154 conjointly rotatable with the shaft and having the cam projection 155 adapted to engage a suitable sliding block 156. The block 156 is suitably guided for reciprocatory movement on the base 150 by guide channels or the like (not shown), and is limited against movement in one direction by the downwardly projecting flange 157 at one-end thereof which engages the end of the block 156. Mounted on the upper surface of the sliding block 156 is a suitable clip member 158 adapted to support the mercury switch indicated generally at 159.

This switch is of the metal envelope type having the insert 160 in the enlarged end thereof supporting the electrode 162, and having the inclined internal runway 163 up which the movable body of mercury 164 is adapted to move to

engage the retained body of mercury 165. The end of the sliding block 156 is provided with a suitable wear plate 166 adapted to be engaged by the cam projection 155 whereby the block is moved to the left as viewed in Figures 8 and 9 to a position such as shown in Figure 9, the cam rotating in the direction indicated by the arrow.

The cam moves at relatively high speed, and consequently the block is shifted rapidly to the position shown in Figure 9. Due to the inertia of the body of mercury 164, the switch is driven thereover with the runway 163 serving as a wedge raising the body of mercury 164 into contact with the retained body 165. The spring 170 biased at opposite ends on pins 172 and 173 carried by the supporting base and the block, respectively, snaps the block 156 back to the position shown in Figure 8 as the cam projection 155 leaves the plate 166. This results in withdrawal of the wedge from under the body of mercury breaking the contact of the bodies 164 and 165 and opening the switch. In actual operation the wedge is driven under and withdrawn at high speeds with respect to the body of mercury 164, and little or no longitudinal movement of the mercury is produced, the making and breaking being accomplished by the movement of the wedge beneath the mercury.

Obviously the switch 159 may be any of the types of switches shown in Figures 1 to 5, inclusive, and the switch shown in Figures 8 and 9 is intended to be representative only of the manner in which such a reciprocating mechanism will be operated in connection with the normal tilting type of switch.

Reference is now directed to Figure 11 in which we disclose a switch structure indicated generally at 175, and of the general type described in connection with the embodiments of the invention shown in Figures 1 to 5. This structure is provided with the extending electrode shank 176, which preferably is threaded adjacent its end, and which has the ceramic spacing member 177 thereon which may be formed independently of, or as an integral part of the ceramic compression disc 178. Threaded over the projecting end of the shank 176 we provide a supporting bracket 180 which may be of any desired shape and size, and which preferably is provided with an aperture 182 whereby it may be secured to a supporting base. By the provision of such a structure, a mechanical support for the switch is provided which can be directly connected to the shank of the electrode, and which is in insulated spaced relation to the metallic envelope. This supporting bracket may be employed for mechanical support, and also for an electrical connection to the shank if so desired, and it is within the purview of the present invention to provide means for securing the bracket to the shank, either as shown in Figure 11 or by using a clamping nut such as the nut 35 of Figure 1, or by soldering or welding the bracket directly to the shank when a construction such as shown in Figures 4 or 5 is provided in the switch. It is to be understood that the bracket 180 of Figure 11 may be employed in place of the clips 158 of Figures 8 and 9 or in place of the supporting clips shown in Figure 10.

Considering Figure 10 in detail, we provide a supporting base 185, having normally extending end portions 186 adapted to respectively support solenoid members 187 and 188, respectively, having the pole faces 189 and 190. Extending between the ends 186 of the base 185 above the

solenoids 187 and 188 are a plurality of parallel guide bars 191 adapted to support a carriage 192 for longitudinal sliding movement thereon. The carriage 192 is provided with spaced supporting means 193 adapted to support suitable metallic envelope type switches 194 and 195, respectively, in opposed relationship. Each of the switches 194 and 195 is provided with the circuit leads 196 and 197, respectively, to the envelope and electrode shank. The carriage 192 is of metallic material, and one terminal of each of the solenoids 187 and 188 is connected to the carriage through flexible electrical connections 198 whereby the carriage is electrically connected between the solenoids and the circuit connected through the conductors 196 to the envelope 195 since the supporting means 193 provides an electrical connection between the carriage and the envelope.

The other terminal of the solenoid 187 is connected through the conductor 199 to the shank 200 of the switch 194, and the second terminal of the solenoid 188 is connected through the conductor 202 to the shank 203 of the switch 195.

In the operation of the structure shown in this figure, the solenoids are alternately energized to produce reciprocatory movement of the carriage 192. Assuming the solenoid 187 to be energized, the pole face 189 thereof actuates the depending armature portion 204 of the carriage, and produces movement of the carriage to the left. This results in driving the wedge portion of the ceramic insert 205 beneath the body of mercury in the switch 194, and as the carriage moves to the left, the mercury 206 is thereby moved into engagement with the retained body of mercury 207. This closes the circuit through the switch 194 and results in energization of the solenoid 188 through the conductor 202 connected to the electrode shank 203, and through the connection 198 to the carriage. At the same time, the movement of the switch 195 with the carriage results in breaking of the circuit through the switch 195, the mercury being carried to the outer end of the switch as indicated at 208, thereby de-energizing the solenoid 187 through disconnection of the mercury from the retained body of mercury in contact with the electrode having the projecting shank 200. As a result the armature portion 209 of the carriage is attracted by the pole face 190 of the solenoid 188, and the carriage will be moved to the right as viewed in Figure 10, whereupon the switch 194 will open and the switch 195 will close, resulting immediately in energization of solenoid 187 to again move the carriage to the left.

Thus the carriage is alternately reciprocated between the solenoids and the switches 194 and 195 are successively opened and closed during each cycle of movement. The circuits controlled by the leads 196 and 197 are consequently also successively opened and closed, and a high speed alternating operation of the switches is thereby produced to operate any suitable mechanism controlled by the circuit connections 197 and 198. Such a structure may be used for sign flashing equipment, for automatic feed or control mechanism, for machinery or the like, or in any other application where one circuit is to be closed as the other is opened, and the operations are to be accomplished successively at high speeds.

It is therefore believed apparent that we have provided certain features of design and construction of the component parts of a switch of this

type which will produce proper heat relationships within the switch itself so as to maintain a cool operating switch even under heavy loads, and which will provide for proper heat dissipation in order to maintain the sealing means at high efficiency. In addition, the present construction provides for proper embedment of the terminal leads for the switch in conjunction with suitable radial and axial insulating and spacing features for preventing flash-overs, and for insuring continued operating performance of the switch for relatively long periods of time.

In addition, the present construction is peculiarly adapted for high speed operation of both small and large capacity switches of this type, and by suitable control of the liquid fill we are able to control the rate of movement of the movable mercury contactor in order to secure precise operation characteristics for the switch.

We are aware that various changes in details of the construction are possible, and various minor modifications may be made in certain constituent parts of the invention. We therefore do not intend to be limited to the precise construction herein shown and described, but only insofar as the invention is defined by the scope and spirit of the appended claims.

We claim:

1. A mercury switch comprising a metallic cup-shaped envelope having an enlarged end, a ceramic insert in said end having an inclined internal throat, an electrode supported solely by said insert and radially insulated from said envelope thereby, resilient sealing means enclosing the end face of said insert and said electrode, a ceramic compression member engaging the outer face of said sealing means and having a tapered portion centered in said sealing means for exerting a radial component of pressure thereon, the end of said envelope being spun over to hold said member axially compressed against said sealing means.

2. In combination, a metallic cup-shaped envelope having an enlarged open end, an arc resisting insert of high thermal and alkaline resistance and poor heat conductivity in said end and having an internal runway terminating in a mercury retaining recess, a body of mercury maintained in said recess, an electrode at the end of said recess supported solely by said insert, a movable body of mercury in said envelope, resilient sealing means compressed about the joint between said electrode and insert and radially about the outer end of said insert, a compression member comprising a refractory insulator of high thermal conductivity in contact with a portion of the rear face of said electrode and pressed axially against said sealing means, and an anhydrous alkaline film over said mercury bodies and capable of volatilizing under an electric arc, whereby the heat developed by arcing between said mercury bodies is dissipated outwardly of the envelope through volatilization of said film and by conduction through said bodies of mercury, said electrode and said compression member.

3. A compression member for a metallic envelope type of mercury switch having an electrode-supporting ceramic insert in one end thereof with resilient sealing means compressed against the outer face of said electrode and ceramic, said electrode having a projecting shank portion, comprising a ceramic member of relatively high heat conductivity having an axially extending frusto-conical portion centered about said shank within said sealing means and having a radial component

of pressure against said sealing means, a disc like portion projecting radially from said frusto-conical portion and pressing axially against the outer radial face of said sealing means, and an axially extending cylindrical portion embracing said shank and serving as an insulating spacer between said envelope and said shank.

4. Sealing means for the end of a metallic envelope type mercury switch having a ceramic insert in one end thereof provided with an annular seat for receiving a disc-like electrode having an extending shank projecting from the outer face of said ceramic, said insert having a tapered annular shoulder at its outer end spaced radially inwardly of the envelope wall, comprising resilient sealing means having a tapered peripheral flange engaged between said envelope wall and said insert shoulder and having a radial portion fitting against the rear face of said insert and electrode, and central portion of said sealing means being spaced from said shank, and a ceramic compression member centered on said shank and having a forward nose portion disposed radially between said sealing means and said shank, an intermediate disc portion for axially compressing said sealing means, and a rear cylindrical portion of reduced diameter about said shank.

5. In a mercury switch of the type in which an electrode is supported solely by a ceramic insert which encloses the same radially, and resilient sealing means is compressed axially against the end of said ceramic and electrode, means for maintaining the opposite faces of said sealing means at substantially uniform temperature comprising a ceramic compression member of high heat conductivity pressed against the outer faces of said sealing means and said electrode.

6. In combination, in a metal envelope type mercury switch, a ceramic insert of high thermal resistance but low heat conductivity carrying an electrode, said electrode being flush with the outer radial surface of said insert and having a projecting shank of small diameter, resilient sealing means disposed against said radial surface of said insert and electrode about said shank, and a ceramic compression member of high heat conductivity forced against the outer surface of said sealing means.

7. An insert for a metallic envelope type of mercury switch comprising a ceramic member having a tapered recess extending axially thereto from one end thereof and terminating at its smaller end in a plurality of coaxial annular internal shoulders, one of said shoulders forming a seat for an electrode disc and the other shoulder spacing said disc from the small end of said recess, and an external frusto-conical surface on said one shoulder disposed radially within the peripheral limits of said insert.

8. In combination, a cup-shaped metallic envelope having an enlarged end portion joined to the body portion by a frusto-conical section, a ceramic insert adapted to fit within said end and having a corresponding frusto-conical section, a tapered recess in the insert terminating in a mercury retaining groove, an electrode disc forming the end wall of said groove and enclosed radially by an annular shoulder on said insert, said shoulder having a short external frusto-conical surface radially spaced from the inner annular surface of said enlarged end of said envelope.

9. In combination, a cup-shaped metallic envelope having an enlarged end portion joined to

the body portion by a frusto-conical section, a ceramic insert adapted to fit within said end and having a corresponding frusto-conical section, a tapered recess in the insert terminating in a mercury retaining groove, an electrode disc forming the end wall of said groove and enclosed radially by an annular shoulder on said insert, said shoulder having a short external frusto-conical surface radially spaced from the inner annular surface of said enlarged end of said envelope, and resilient compressible sealing means radially closing the outer face of said disc and said shoulder and having a tapered peripheral flange engaging about said last-named frusto-conical section.

10. A switch comprising a metallic envelope carrying a ceramic insert in its open end, an electrode supported solely by said insert and having a shank projecting axially out of the end of said envelope, a ceramic compression disc holding said insert in position and having a portion forming an annular cylinder about the shank, the outer end face of said cylinder being axially recessed about the end of said shank to form a lead wire 5 receiving recess radially enclosed by said cylinder.

11. A switch comprising a metallic envelope carrying a ceramic insert in its open end, an electrode supported solely by said insert and having a shank projecting axially out of the end of said

envelope, a ceramic compression disc holding said insert in position and having a portion forming an annular cylinder about the shank, the outer end face of said cylinder being axially recessed about the end of said shank to form a lead wire 5 receiving recess radially enclosed by said cylinder, and cementitious material applied over the end face of said cylinder and the end of said shank for embedding the end of said lead wire therein.

12. In combination, a metallic envelope switch having an insert in one end thereof, an electrode supported by the insert and having a shank projecting outwardly of the end of said envelope, an annular insulating washer on said shank having 15 an axial length such that it projects beyond said envelope, and a supporting bracket secured to the shank and spaced from said envelope by said washer.

13. In combination, a metallic envelope switch 20 having an insert in one end thereof, an electrode supported by the insert and having a shank projecting outwardly of the end of said envelope, an annular insulating washer on said shank projecting beyond said envelope, and a supporting 25 bracket threaded onto the end of said shank against said washer.
